US00D789519S

(12) **United States Design Patent** (10) **Patent No.:** **US D789,519 S**
(45) **Date of Patent:** **** Jun. 13, 2017**

(54) **MEDICAMENT INJECTION DEVICE**

(71) Applicants: **SANOFI**, Paris (FR); **REGENERON PHARMACEUTICALS, INC.**, Tarrytown, NY (US)

(72) Inventors: **Jochen Ratjen**, Nacka (SE); **Katja Wessel**, Stockholm (SE)

(73) Assignee: **SANOFI**, Paris (FR)

(**) Term: **15 Years**

(21) Appl. No.: **29/582,552**

(22) Filed: **Oct. 28, 2016**

(57) **CLAIM**

The ornamental design for a medicament injection device, as shown and described.

DESCRIPTION

The file of this patent contains at least one drawing executed in color. Copies of this patent with color drawings will be provided by the Office upon request and payment of the necessary fee.

FIG. 1 is a perspective view of the injection device viewed from the front and right of and above the injection device; FIG. 2 is a bottom plan view thereof;

FIG. 3 is a top plan view thereof;

FIG. 4 is a perspective view of a second embodiment of the injection device viewed from the front and right of and above the injection device;

FIG. 5 is a bottom plan view thereof;

FIG. 6 is a top plan view thereof;

FIG. 7 is a perspective view of a third embodiment of the injection device viewed from the front and right of and above the injection device;

FIG. 8 is a bottom plan view thereof; and,

FIG. 9 is a top plan view thereof.

The broken lines shown in the figures are for the purpose of illustrating portions of the article and forms no part of the claimed design. The broken line, which defines the bounds of the claimed invention, forms no part of the claimed design.
